No. 36,712.

Patented December 29, 1903.

UNITED STATES PATENT OFFICE.

EDWARD F. EBERLE, OF ERIE, PENNSYLVANIA.

DESIGN FOR A PANEL BORDER FOR PHOTOGRAPHS, PICTURES, AND ILLUSTRATIVE MATTER.

SPECIFICATION forming part of Design No. 36,712, dated December 29, 1903.

Application filed November 25, 1903. Serial No. 182,692. Term of patent 3½ years.

To all whom it may concern:

Be it known that I, EDWARD F. EBERLE, a citizen of the United States, residing at Erie, in the county of Erie and State of Pennsylvania, have invented a new, original, and ornamental Design for a Panel Border for Photographs, Pictures, and Illustrative Matter, of which the following is a specification, reference being had to the accompanying drawing, forming a part thereof.

The design is shown in the accompanying drawing, which illustrates a plan view thereof. What is claimed as new is—

The ornamental design for a panel border for photographs, pictures and illustrative matter, substantially as herein shown.

EDWARD F. EBERLE. [L. S.]
